(57) **CLAIM**

The ornamental design of a lavatory basin, as shown and
described.

DESCRIPTION

FIG. 1 is a perspective view of the lavatory basin;
FIG. 2 is a right side elevational view of the lavatory basin,
the left side elevational view being a mirror image of the
right side elevational view;
FIG. 3 is a front elevational view of the lavatory basin;
FIG. 4 is a rear elevational view of the lavatory basin;
FIG. 5 is a top plan view of the lavatory basin; and,
FIG. 6 is a bottom view of the lavatory basin.
